UNITED STATES PATENT OFFICE.

JAMES P. KENDRICK, OF FAYETTE, MISSOURI.

FEED-TROUGH.

1,142,176.

Specification of Letters Patent.

Patented June 8, 1915.

Application filed May 28, 1914. Serial No. 841,590.

To all whom it may concern:

Be it known that I, JAMES P. KENDRICK, a citizen of the United States, residing at Fayette, in the county of Howard and State 5 of Missouri, have invented certain new and useful Improvements in Feed-Troughs, of which the following is a specification.

This invention relates to feeding devices and more specifically to sanitary feed 10 troughs.

The object of my invention is to provide a sanitary feed trough of substantial metallic construction. It is constructed of durable rust-proof metal and there are no 15 crevices or cracks in which filth may accumulate. Openings are provided for putting feed into the trough. It is readily cleaned, and individual roof portions are placed over the several feed openings to prevent foreign 20 substances from falling into the feed. These roof portions also prevent rapid evaporation due to the sun's rays.

Other objects of this invention not at this time more particularly enumerated, will be 25 clearly understood from the detailed description and drawings forming a part of this specification.

Furthermore, this invention consists in the novel arrangement and combination of parts 30 more particularly described in the following specification and embodied in the claim appended hereunto and forming a part of this application.

Referring now to the drawings, which are 35 merely illustrative of my invention Figure 1 is a side elevation of my feed trough, while Fig. 2 is a top plan view of the same. Fig. 3 is an end elevation. Fig. 4 is a cross-sectional view taken on the line 4—4 of Fig. 2.

Referring further to the drawings, wherein 40 similar reference characters designate similar parts throughout the respective views, 1 designates the body portion of my trough which is tube shaped and may be of any length desired. The said body portion 45 is formed preferably of a rectangular blank metal sheet having an in cut portion at a certain point upon both sides and extending to the ends thereof. Spaced apart along the 50 edges of both longitudinal sides of said blank are cut a plurality of U-shaped indentations. Between each of said indentations thus formed is left a projecting tongue 6, so that when the sides of the blank are folded 55 upwardly and inwardly in the shape of a

tube, the said tongue members 6 may be bent upwardly at an angle radial to the axis of said body portion 1. A ridge piece 7 is inserted between the two rows of upwardly extending tongue members 6, to which it is 60 secured by means of rivets 6^a. The U-shaped indentations 5 thus form a line of individual feed openings on both sides of said ridge piece. The inwardly cut portions on both sides and at both ends of the blank are 65 adapted to form openings 4 when the blank is bent in the manner heretofore described, such openings being provided for the introduction of feed into the trough. At both ends and below said openings 4 are fixed 70 end members 2 adapted to close said ends. Said end members extend outwardly and downwardly from the sides of the body portion 1 to a point beneath the said body portion, thereby forming legs for the trough. 75 The said end members are of sheet metal, and are bent inwardly on the sides and bottom at 3 for the purpose of reinforcing the same. Above each of the feed openings or 80 U-shaped indentations 5, and extending outwardly sufficiently to form a shed above said openings are mounted roof portions 8. To form said roof portions 8 I bend a blank metal sheet, centrally thereof at 8^a so that the sides are at right angles to each other, 85 each of said sides thence being bent inwardly toward each other at 8^b, thence downwardly in parallelism at 8^c, thereby forming the standards 8^d which are adapted to support 90 said roof portion by being secured upon said ridge piece 7 by means of rivets 9.

Having now described and pointed out the new and useful features of my invention, I do not limit myself to the shape of certain parts where the shape is not essential, nor 95 do I restrict myself to the exact details of construction shown and described, but mean and intend to claim all equivalents and variations thereof not departing in principle from my invention and falling within the 100 purview of the appended claim.

What I claim as my invention and desire to secure by Letters Patent is:

In a feed trough, in combination, a tubular body portion, upstanding flanges formed 105 longitudinally upon the ridge of said body portion, said flanges and said body portion formed with an in cut portion U-shaped in outline, said flanges and said body portion formed with cutout portions upon the ends 110

thereof, a horizontally disposed ridge piece interposed between said flanges, a plurality of triangularly shaped roof portions formed with depending flanges diametrically opposite the apex of said roof portions, said flanges adapted to be secured upon said ridge piece above said incut portion, and a standard mounted upon both ends of said

tubular body portion adapted to close said ends.

In testimony whereof I affix my signature in presence of two witnesses.

JAMES P. KENDRICK.
